UNITED STATES PATENT OFFICE.

ALBERT KRASA, OF MICHIGAN CITY, INDIANA, ASSIGNOR TO UNION SPECIAL MACHINE COMPANY, OF CHICAGO, ILLINOIS, A CORPORATION OF ILLINOIS.

SEWING-MACHINE.

1,197,038.

Specification of Letters Patent. Patented Sept. 5, 1916.

Application filed May 12, 1913. Serial No. 767,183.

To all whom it may concern:

Be it known that I, ALBERT KRASA, a citizen of the United States, residing at Michigan City, in the county of Laporte, State of Indiana, have invented certain new and useful Improvements in Sewing-Machines, of which the following is a description, reference being had to the accompanying drawing and to the figures of reference marked 10 thereon.

The invention relates to new and useful improvements in sewing machines, and more particularly to the looper mechanism for a cylindrical bed plate machine, such as shown 15 for example, in the patent granted L. Muther, R. G. Woodward, and E. C. Holland, May 25th, 1897, No. 583,415.

An object of the invention is to provide 20 a looper-supporting shaft and operating devices therefor, which are so constructed and arranged that said looper shaft may have an extended bearing in the standard of the machine.

In the drawings which show by way of 25 illustration, one embodiment of the invention, Figure 1 is a vertical sectional view longitudinally of the bed plate, showing the lower part of a sewing machine having my improvements applied thereto, the feeding 30 mechanism being omitted for the sake of clearness; Fig. 2 is a view showing the means for oscillating the looper shaft; Fig. 3 is a detail showing the looper shaft and the bearing therefor, in plan view.

The sewing machine to which my invention 35 is applied, consists of a supporting base 1, from which rises a standard 2. Mounted in the standard 2 in suitable bearings therein is a main shaft 3. Projecting laterally 40 from said standard 2 is a cylindrical bed plate 4. This cylindrical bed plate, as shown in the patent above referred to, extends to a point slightly beyond the needle 5.

The looper-supporting shaft 6 is mounted 45 to rotate in a bearing 7 carried by the cylindrical bed plate adjacent its outer end, and also in a bearing 8 carried by the cylindrical bed plate at its inner end, or where said cylindrical bed plate is attached to the 50 standard 2. The looper-supporting shaft 6 at its inner end is provided with an operating yoke 9. This yoke is preferably made so as to fit snugly on the end of the shaft, and is welded thereto. Instead, however, of 55 welding the yoke to the looper shaft, said

yoke and looper shaft may be made from a single piece of metal.

The essential feature of construction consists in forming the yoke integral with the end of the shaft, and this may be accomplished in either way above noted. This yoke has a laterally projecting arm carrying a stud 10, which coöperates with an eccentric strap 11. The eccentric strap 11 in turn coöperates with an eccentric 12 on the 60 main shaft 3. As the main shaft 3 rotates, this eccentric strap 11, through the yoke 9, will oscillate the looper shaft in its bearings. The yoke 9 is also provided with an ear 13, which is preferably arranged substantially in axial alinement with the longitudinal axis of the looper-supporting shaft. A cross shaft 14 is mounted in suitable bearings in the standard 2, and is parallel with the main shaft 3. On this cross shaft 14 is 65 a lever 15. The lower end of the lever 15 is slotted as at 16. A link 17 is forked at its inner end, and is pivoted to the ear 13. The outer end of the link 17 is pivotally supported 70 connected to a rod 18, adjustably supported 75 in the slot 16.

The lever 15 at its upper end is connected to an eccentric strap 19, which coöperates with an eccentric 20 on the main shaft 3. As the main shaft 3 rotates, the lever 15 will be 80 oscillated, and through the link 17, will move said looper-supporting shaft endwise in its 85 bearings. The amount of movement imparted to the looper shaft may be varied by adjusting the position of the rod 18 in the 90 slot 16.

On the outer end of the looper shaft 6 and adjacent the needle 5, is a looper carrier 21, which supports a looper 22. This looper carrier 21 is adjustably held on the end of the 95 shaft 6 by a set screw 23. The looper is so mounted on the carrier 21 that the oscillating movements of the looper shaft will move the looper into and out of the needle loop, while the endwise movements of the 100 looper shaft will give to said looper its needle-avoiding movements. When the looper shaft is in place, the looper carrier, by loosening the set screw 23, may be adjusted longitudinally of said shaft to bring 105 said looper into proper coöoperative relation with the needle 5, after which the set screw 23 may be used for locking the carrier to the shaft, so that it is rigidly connected thereto.

In the patent above referred to, it will be 110

noted that the yoke for oscillating the looper shaft and for moving the same endwise, is clamped to the end of the looper shaft, and this requires a collar of considerable width, 5 and necessarily restricts the amount of bearing surface of the looper shaft in the cylindrical bed plate at the inner end of the shaft. By my present invention, the yoke is welded or otherwise formed integral with the end 10 of the shaft, and as a consequence said connection between the yoke and the shaft may be made very much smaller. This gives space for an additional bearing for the looper shaft. This additional or auxiliary bearing 24 is clamped to the plate 25 cast integral with the cylindrical bed plate, by clamping bolts 26, which, as herein shown, are three in number. The bearing 24 projects into the interior of the standard 2, and 20 to a point adjacent the end of the looper shaft. The bearing 8 which is formed as a part of the plate 25, projects outwardly, and this forms an extended bearing for the shaft 6.

25 The bearing 24 is formed with a rib 27, which engages a socket 28 in the plate 25 to aid in holding the bearing in fixed relation with the plate 25.

30 By the above construction, wherein the yoke is formed integral with the inner end of the looper shaft, the looper is made adjustable on the looper shaft, so it may be properly set relative to the needle, and I am thereby able to produce a looper shaft having 35 a yoke formed integral therewith, so as to afford an extended bearing surface for the looper shaft at the inner end thereof, and at the same time secure the proper adjustments between the looper carrier and 40 the looper, to properly position the looper relative to the needle.

45 While I have described the yoke 9 as formed integral with the shaft, particular attention is called to the fact that the shaft 5 is connected directly to one arm of the yoke, and by this direct connection of the shaft 6 to the yoke, I am able to provide further space for the inwardly extending auxiliary bearing 24.

50 It will be obvious that from certain aspects of the invention this yoke may be otherwise secured to the shaft 6, than by welding or formed integral therewith, as above described.

55 Having thus described my invention, what I claim as new and desire to secure by Letters Patent, is:—

60 1. A sewing machine including in combination, a looper shaft, means for supporting said looper shaft between its ends, whereby said looper shaft may be oscillated and moved endwise, a yoke having one of its arms formed integral with the inner end of the shaft, means connected to the arm attached 65 to the shaft for oscillating the same, and

means connected to the other arm of the yoke for moving the shaft endwise, and a looper carrier mounted on the other end of said shaft.

2. A sewing machine including in combination, a looper shaft, means for supporting said looper shaft between its ends, whereby said looper shaft may be oscillated and moved endwise, a yoke having one of its arms formed integral with the inner end of the shaft, means connected to the arm attached to the shaft for oscillating the same and means connected to the other arm of the yoke for moving the shaft endwise, and a looper carrier mounted on the other end of said shaft, said looper carrier being adjustable lengthwise of the shaft.

3. A sewing machine including in combination, a standard, a cylindrical bed plate projecting laterally therefrom, a supporting plate for attaching said bed plate to the standard, a bearing carried by said supporting plate and projecting into said standard, a looper shaft mounted in said bearing, a yoke formed integral with the inner end of said shaft adjacent said bearing, means connected to said yoke for oscillating said shaft and for moving said shaft longitudinally, and a looper carrier adjustably connected with the outer end of said shaft.

4. A sewing machine including in combination, a standard, a cylindrical bed plate projecting laterally from said standard, a supporting plate for attaching said cylindrical bed plate to said standard, a bearing projecting outwardly from said plate, a bearing attached to the inner face of said plate and projecting into said standard, a looper shaft mounted in said bearings, a yoke formed integral with the inner end of said shaft, means engaging said yoke for oscillating said shaft and for moving said shaft endwise in said bearing, a bearing near the outer end of said bed plate for said shaft, and a looper carrier adjustably mounted on the outer end of said looper shaft.

5. A sewing machine including in combination a looper shaft, means for supporting the same, a yoke, one arm of which is directly attached to the end of the shaft, and a ball mounted eccentrically upon said arm, whereby said yoke may be oscillated, the other arm of said yoke having a connection whereby said shaft may be moved endwise.

6. A sewing machine including in combination a looper shaft, means for supporting the same, a yoke, one arm of which is directly attached to the end of the shaft, a ball mounted eccentrically upon said arm, whereby said yoke may be oscillated, and a swivel connection at the opposite end of the yoke, whereby said yoke may be moved longitudinally.

7. A sewing machine including in combination a looper shaft, means for supporting the same, a yoke, one arm of which is directly

- attached to the end of the shaft, a ball mounted eccentrically upon said arm, whereby said yoke may be oscillated, a swivel connection at the opposite end of the yoke, whereby said 5 yoke may be moved longitudinally, means connected to said ball for oscillating the looper shaft, and means connected to said swivel connection for moving said looper shaft longitudinally.
- 10 8. A sewing machine including in combination, a looper shaft, means for supporting said shaft, a yoke formed upon one end of

said shaft, means to operate said yoke in two different directions, a looper support mounted upon the opposite end of said shaft and 15 means whereby said looper support is adjusted in two directions.

In testimony whereof I affix my signature in the presence of two witnesses.

ALBERT KRASA.
